FOOD MIXER OR THE LIKE

James R. Cochrane, Chicago, Ill., assignor to Sunbeam Corporation, Chicago, Ill., a corporation of Illinois

Filed July 11, 1963, Ser. No. 75,748

Term of patent 14 years

(Cl. D44—1)

FIG. 1 is a left side perspective view of a food mixer or the like embodying my new design;

FIG. 2 is a front elevational view thereof;

FIG. 3 is a top plan view thereof;

FIGS. 4 and 5 are right side and rear elevational views thereof, respectively; and

FIG. 6 is fragmentary sectional view taken along line 6-6 of FIG. 2.

The essential features of my design reside in those portions shown by full lines.

I claim:

The ornamental design for a food mixer or the like, substantially as shown and described.
